UNITED STATES PATENT OFFICE.

THOMAS COOPER, OF NEW YORK, N. Y.

AUXILIARY FIRE-ALARM SYSTEM.

SPECIFICATION forming part of Letters Patent No. 416,444, dated December 3, 1889.

Application filed March 11, 1889. Serial No. 302,803. (No model.)

To all whom it may concern.

Be it known that I, THOMAS COOPER, a citizen of the United States, residing at New York, in the county of New York and State of New York, have invented certain new and useful Improvements in Auxiliary Fire-Alarm Systems; and I do hereby declare the following to be a full, clear, and exact description of the invention, such as will enable others skilled in the art to which it appertains to make and use the same.

This invention relates to a novel system of auxiliary fire-alarm telegraphs.

The invention consists in the organization and arrangement of devices, substantially as hereinafter fully described and claimed, whereby each of the auxiliary stations in any one circuit is adapted to directly notify the engine-house at which such circuit centers of the fact of the fire-call, the precise location of the same in the district, and at the same time the general fire-alarm circuit of the city has the same signal indicating the district sent to all the engine-houses which are on the general circuit.

In the drawings which form part of this specification, Figure 1 is a front elevation of the apparatus intended to be placed in the engine-house. Fig. 1^a is an elevation of the upper portion of Fig. 1 with the indicator-disk removed; and Fig. 2 is a diagram indicating the arrangement of circuits, and clearly setting forth the nature of the present invention.

More particularly, my invention is as follows: I locate throughout a predetermined district a number of the ordinary form of the call-boxes C, which consist merely of a make-and-break wheel and suitable device for rotating said wheel. The particular construction of such boxes forms no part of the said invention, as there are a number of them on the market, any one of which will fulfill the purpose for which I intend it. These boxes are all connected into the auxiliary circuit, which terminates in an electro-magnetic signaling or indicating apparatus at the engine-house to which the auxiliary circuit leads, and in said circuit is placed a suitable battery B, of sufficient power to perform the necessary functions, hereinafter set forth.

As the ordinary practice in auxiliary systems is to group the stations on the auxiliary circuit all within a convenient distance of one of the fire-alarm street-boxes of the general fire-alarm circuit, I also adopt this expedient and place the fire-alarm box F at a convenient point in the neighborhood of the stations on the auxiliary circuit. I wish to distinctly state, however, that the general city circuit has no connection whatever with the auxiliary circuit. Nor is the apparatus at the engine-house connected in any way other than mechanically to the said general city circuit.

As stated, I locate at the engine-house an electro-magnetic indicating device, which conveniently consists of a disk D, adapted to be rotated one step for each stroke of the gong, which is of the electro-mechanical character, and this disk D has upon it as many numerals as there are boxes on the auxiliary circuit. A variety of constructions may be adopted for the step-by-step rotation of the indicating-disk D; but I prefer the form shown. This is constructed in accordance with Letters Patent No 334,380, dated January 12, 1886. The energy of the wound-up spring tends to rotate the gear-wheel 20 in the direction of its arrow. A small pinion (not shown) meshing with wheel 20 is mounted on a shaft 21, and on this is keyed an escapement-arm 22, which also acts as a crank, one end being connected by a link 23 to the L-shaped striker or hammer 24, which rocks on a stud 25. In the path of arm 22 are two oscillating detent-heads 26 27, supported on arbors journaled in the frame and connected by mutually-engaging rock-arms, one of which is oscillated directly by the armature 28 of the controlling-magnet 29. The normal position is shown by full lines in Fig. 1^a, the armature 28 being in attracted position. When the circuit of magnet 29 is opened, the armature retracts and throws the heads 26 27 into the position shown in dotted lines. The arm 22 is thus released by head 27 and flies around by the power of the spring until caught by head 26, causing the hammer to strike a sudden powerful blow on the gong. The new position of arm, link, and hammer is shown by dotted lines. When the circuit of magnet 29 is again closed, the heads 26 27

are again oscillated to normal position by the armature, head 26 releasing the arm 22, which flies over against head 27 and remains there until the magnet-circuit is again opened. 5 This construction gives me a very simple step-by-step motion for my indicator. Upon the mainspring-shaft 30, I fix a gear-wheel 31, and meshing with this is a pinion 32, which is fixed on the end of sleeve 33, which is 10 mounted on the pin 34 and carries the indicating-disk D with it. The disk D thus receives a step-by-step movement, always in one direction and through the same number of degrees, for each break and make of the magnet-circuit—*i. e.*, the auxiliary line. 15

As the system is a closed-circuit system, it is the usual practice not to use the numerals 1 or 2 for signaling purposes, and I therefore make the series of auxiliary call-boxes without such numbers. 20

At a suitable point on the frame carrying the electro-mechanical gong—preferably fixed to the gong itself or to its central stud—I locate an ordinary make-and-break mechanism, 25 such, for instance, as that ordinarily used in fire-alarm boxes for street service.

In Fig. 1 I have shown the make-and-break wheel W, its driving-train, and propelling-spring s. The wheel W, with its contacts v, 30 is directly in the general city circuit, which of course includes the box F of the district to which the particular auxiliary circuit shown belongs. The make-and-break mechanism placed at the indicator in the engine-house is arranged to send the same signal over the general city circuit as the box F. 35

Each of the station call-boxes C in the auxiliary circuit of course sends in a different signal to the indicator at the engine-house. 40 This indicator is arranged to display at a window (represented in Fig. 1 by dotted lines) the number corresponding to the box which has sent in the call. The make-and-break mechanism at the engine-house is shown 45 with a detent d on a pivoted lever l, the detent taking into one of the wheels of the make-and-break train. A lever m is pivoted in a suitable manner, so that it is moved by a projection p on the indicator-disk D as the latter 50 rotates, and the projection p is so placed as to push the lever on the third stroke of the gong; or, in other words, on the break in the circuit given at each signal. The lower end 55 of the lever m is provided with a wedge-shaped toe adapted in its movement to lift the pivoted lever l, so as to release the clock-train and set the make-and-break wheel W in motion.

The result of the foregoing construction and 60 arrangement is that when any one of the boxes on the auxiliary circuit is operated its number is immediately indicated at the engine-house, thereby giving notice of the particular location of the fire, and in addition 65 the independent make-and-break wheel W is at the same moment set in operation, so that the number indicating the fire-alarm box F

is also signaled over the general city circuit, and all engine-houses thus notified of the district within which the fire has occurred. I thus 70 accomplish immediate accurate notice to the nearest engine-house of the precise location of the fire, and at the same time give notice to all the engine-houses of the fire-alarm box nearest to which the fire has occurred. These 75 results are accomplished in the simplest possible manner and with the simplest possible devices, using only a small battery on the auxiliary circuit and a single electro-magnet for the purpose of notifying and indicating 80 the location.

I claim as my invention—

1. The auxiliary fire-alarm system, comprising a main circuit, a closed independent auxiliary circuit, including a battery and individual call-boxes, at the auxiliary stations, and a visual indicator at the engine-house, consisting of an electro-magnet in the auxiliary circuit, an oscillating armature therefor, an indicator-motor having a step-by-step escapement controlled by said oscillating armature, and a rotary indicator-disk geared to the shaft of the indicator-motor and adapted for direct movement thereby in a single direction only, in combination with an independent motor 95 having a make-and-break wheel included in the main circuit, adapted to signal the general locality of the said auxiliary boxes, and a detent for the same mechanically interposed between the said independent motor and the 100 indicator-disk and adapted for operation by the movements of said indicator mechanism to release the independent motor, substantially as described.

2. The auxiliary fire-alarm system, comprising a main circuit, a closed independent auxiliary circuit, including a battery and individual call-boxes, at the auxiliary stations, and a visual indicator at the engine-house, consisting of an electro-magnet in the auxiliary circuit, an oscillating armature therefor, an indicator-motor having a step-by-step escapement controlled by said oscillating armature, and a rotary indicator-disk geared to the shaft of the indicator-motor and adapted 110 for direct movement thereby in a single direction only, in combination with an independent motor having a make-and-break wheel included in the main circuit adapted to signal the general locality of the said auxiliary boxes, 115 a detent for said independent motor, an interposed pivoted lever for lifting the detent and releasing the motor, and a tripper on the rotating shaft of the indicator-disk arranged to strike said lever only after more than one 120 break in the auxiliary circuit, substantially as described.

In testimony whereof I affix my signature in presence of two witnesses.

THOMAS COOPER.
